UNITED STATES PATENT OFFICE.

DONA BOISVERT, OF PROVIDENCE, RHODE ISLAND.

ELECTRIC SEMAPHORE.

SPECIFICATION forming part of Letters Patent No. 757,722, dated April 19, 1904.

Application filed October 13, 1902. Serial No. 127,128. (No model.)

To all whom it may concern:

Be it known that I, DONA BOISVERT, a subject of the King of Great Britain, residing at Providence, county of Providence, State of Rhode Island, have invented certain new and useful Improvements in Electric Semaphores; and I do hereby declare that the following is a full, clear, and exact description of the invention, such as will enable others skilled in the art to which it appertains to make and use the same.

My invention relates to a semaphore adapted to be used for railway signaling, and especially adapted for use at a short distance from the station at which the semaphore is operated.

The object of my invention is to provide a semaphore which is readily operable by pressing a button from the station and which has means connected therewith for notifying the operator at the station that the arms of the semaphore have turned, and, furthermore, means are provided for notifying the operator at the station at what position the arms are finally set after the apparatus has been operated, so that in this manner there is at no time any doubt as to whether upon depressing the button the semaphore actually turns into the proper position or not.

A further object of my invention is to provide means for shielding the semaphore against injury by wind, rain, or other atmospheric agencies.

A further object of my invention is to simplify the construction of the apparatus so as to provide a minimum of parts which are liable to get out of order and to enable the same to be worked by a battery-current of small power.

My semaphore is of that type which are mechanically operated but electrically controlled—that is to say, in which the power needed for operating the semaphore is due to a mechanical motor, especially one, such as a clock weight or spring, which is wound up at intervals, while the means for releasing and controlling the said motor are operated by electricity.

My invention consists in the main in a semaphore arm or pair of arms mounted on a horizontal axle, rotatable in journals carried in a suitable casing and having connected therewith gearing and a suitable weight-motor or

other like device, in combination with an escapement-wheel and a pallet or pawl adapted to strike against the teeth of said wheel and to hold it against turning, except when the 55 said pawl is drawn back by the operation of a subsidiary motor, which is released by an electrically-operated click and so arranged as to be prevented from turning more than one revolution at each depression of the button 60 which operates said click, the said button being located in the station from which the semaphore is to be operated and in the same battery-circuit with the magnet which operates the click. 65

My invention further consists in providing a safety device or means of notification to the operator in the station that the semaphore-arms have been duly operated or depressed by the depression of the button, said 70 means comprising a bell located in the station and a make-and-break device, which is operated by the turning of said pallet-wheel, so as to cause the bell to ring at each partial revolution thereof, and, furthermore, to cause 75 the bell to ring continuously when the semaphore-arms are set at "danger."

My invention further consists in providing a semicircular hood or covering, which 80 encloses the uppermost arm of the semaphore when it is vertically set and prevents the possible destruction thereof by the wind.

My invention further consists in the construction and combination of parts herein-after described and more particularly set 85 forth in the claims.

In the drawings accompanying this specification I have illustrated one means of carrying out my invention, and herein—

Figure 1 is a perspective view of my improved semaphore complete as located on a line of railway. Fig. 2 is a transverse vertical section through the case of the semaphore, taken on the line 2-2 of Fig. 3 and looking toward the front. Fig. 3 is a longitudinal central section through the casing and semaphore, taken in the plane of the main axle. Fig. 4 is a detailed view, in side elevation, of the secondary motor which operates the pallet and the electrically-operated click 95 therefor. Fig. 5 is a front elevation of the same. Fig. 6 is a detailed longitudinal sec- 100

tional elevation of the make-and-break device which operates the return-signal.

The semaphore comprises, as shown in the drawings, a pair of radial arms 7, which are mounted on a horizontal axle 8, rotatable in a journal-bearing 9, carried upon a pedestal 10, within a box or casing 11, which is sustained on the upper end of a tower 12. The semaphore-arms are keyed fast to the axle 8 by any suitable means—as, for instance, by the squared portion 13—which prevents them from turning thereon. The rear end of the axle 8 projects beyond the bearing 9 and has fixed thereto the pallet-wheel 14, having four radial arms 15, with which engages a pallet 16, pivoted at 17 upon a stationary lug projecting from the side of the box. Furthermore, the axle 8 has keyed thereto a gear-pinion 18, which meshes with a large gear 19, which turns loosely on an arbor 20, which is supported by journal-posts 21 and 22, resting on the floor of the box or casing 11. The gear-wheel 19 has fixed to one side thereof a ratchet-wheel 23, and keyed to the arbor adjacent to the wheel 23 is a drum 24, around which is wound a cord 25, from the end of which depends a weight 26 of suitable mass for turning the semaphore-arm through the medium of the gearing. To the drum 24 is fixed at the end adjacent to the wheel 23 a second ratchet-wheel 27, whose teeth face in the opposite direction from the ratchet-wheel 23, as shown, and which is operatively connected therewith by a pawl 28, which is pivoted at 29 to the face of the wheel 23 and held in engagement with the teeth of the wheel 27 by a spring 30, also mounted on the wheel 23. The rear end of the arbor 20 has a squared stud 31 formed thereon, which is for the purpose of enabling the insertion of a crank-handle 32 for winding up the arbor when it becomes run down. The weight 26 is arranged to pass through a hole 33 in the bottom of the box and into a tubular column 34, which is secured to the bottom and passes downwardly to the ground or as far as the length of the cord 25 may require. It will be seen that this connection causes the axle of the semaphore to be rotated right-handedly, as shown in Fig. 2 looking from the rear, and in order to prevent possible backward motion the ratchet-wheel 23 is provided with a pawl 35, pivoted at 36 to a stationary lug on the side of the casing.

The ordinary motion of the semaphore-arms caused by the weight is prevented by the pallet 16, the upper arm 37 of which abuts against one of the radial arms 15, except when drawn out of engagement therewith by the electrically-operated releasing device, which is illustrated in detail in Figs. 4 and 5. Upon a secondary axle 38, journaled on posts 39 at the side of the main axle, is carried a drum 40, which has wound thereon a cord 41, from which depends a weight 42, and the front end 65 of the axle has keyed thereto a wheel 43, which

has at one point thereof a radial tooth 44, with which coacts the releasing-click 45. This click is of three-sided form, as shown in Fig. 4, the middle member 46 of which slides in stationary guides 47, and its upper and lower members (designated, respectively, 48 and 49) project into the vicinity of the rim of the wheel 43, at opposite sides thereof, as shown, and are so disposed that one of them must in all positions of the click engage with the tooth 44 to prevent the wheel 43 from turning. To the upper end of the click is attached an armature of soft iron 50, immediately adjacent to which and above the same is located an electromagnet 51, which is operated by an electric circuit 52, energized by a battery 53 and having a press-button or other contact-making device 54 therein at the operating-station. Furthermore, the wheel 43 has at a point thereof separated by an arc of ninety degrees from the tooth 44 a transverse pin 55, on which is journaled the pitman 56, whose other end is operatively connected, as at 57, to the upper arm 37 of the pallet 16.

The safety device which operates the return-signal of the semaphore comprises a make-and-break contact of any suitable form, that preferably used by me being shown in Fig. 6, in combination with bosses formed around the periphery of the pallet-wheel, which are adapted to depress said contact device and make the circuit as they pass by the same. The contact device (shown in Fig. 6) comprises any suitable box or casing 59, which is carried on the upper side of the journal-box 100 of the axle 8, as shown, and has a tubular portion 60, in which is mounted a reciprocating bolt 61, whose outer end 62 is flattened and is adapted to project into a position in proximity to the front face of the pallet-wheel. The bolt 61 is formed tubular, and in it reciprocates a secondary or contact bolt 63, which has on its forward end a contact-plate 64, located opposite a stationary contact-plate 65, carried by the front wall of the box 59 and insulated therefrom. Around the shank of the bolt 63 is mounted a compression-spring 66, the ends of which press, respectively, against the back of the plate 64 and end of the bolt 61, and the motion of the bolt 63 is limited with respect to the bolt 61 by the transverse pin 67, operating in a longitudinal slot 68 in the side of the bolt 61, as shown, the object being to produce a spring-contact, so that the depression of the bolt 61 shall cause the contact-plate 64 to be pressed resiliently against the plate 65 to make electrical contact therewith. The respective contact-plates 64 and 65 are electrically connected with the terminals of a circuit 69, which may be energized from the same battery 53 and has at the station end a bell or other signaling device 70 located therein, so that when the bolt 61 is depressed to bring the two contact-plates together the bell 70 will be rung. 130

Coöperating with the bolt 61 to produce this effect are a series of bosses 71 on the face of the pallet-wheel adjacent to the contact device, these being four in number, and these are located at the bases of the respective arms 15, while two others (designated 71^a) are at points slightly in advance of the two diametrically opposite arms 15, which are adapted to be caught by the pallet 16 when the semaphore is in safety position. It will be seen, therefore, that the four bosses 71 will successively strike and depress the bolt 61 whenever the pallet 16 is withdrawn, and, moreover, the bosses 71^a are opposite the contact-bolt when the semaphore is stationary and in danger position, so that the bell 70 will be continuously rung when the semaphore is in this position.

The mode of operation of my improved semaphore as thus far described is as follows: When the operator desires to change the position of a signal, he depresses the button 54 within the station, which causes the magnet 51 to be energized, and thereby raises the click 45, so as to release the tooth 44 of the wheel 43, and thereby turns the latter through one hundred and eighty degrees, whereupon it will be brought to a stop by the engagement of the tooth 44 with the lower member 49 of the click. In this position the parts will be as shown in dotted lines in Fig. 5, and the weight 26 will thereupon cause the semaphore-arms to revolve till the arm 15 of the pallet-wheel strikes against the lower member 58 of the pallet, in which position it will be retained until the button 54 is released. The operator will keep his finger on the button till the bell rings, which will be the case when one set of arms 15 are in vertical position and retained in this position by the lower arm 58 of the pallet, as shown in Fig. 5, and in which position a boss 71 will engage the bolt 61. As soon, therefore, as the operator hears the bell ring he releases the button 54, which permits the click 45 to drop again, whereupon the wheel 43 will revolve another half-revolution until brought to a stop by the tooth 44 coming in contact with the upper member 48 of the click, and the pallet 16 will be returned to its original position, thus releasing the arm 15 of the pallet-wheel which rests against the arm 58 of the pallet and permitting the quarter-revolution of the pallet-wheel to be completed until the next arm 15 rests against the pallet 16. At this last point the bell will cease ringing, owing to the boss 71 passing beyond the contact-bolt 61; but in case the signal is being turned into the danger position the boss 71^a will depress the contact-bolt continuously, and thus keep the bell 70 in continuous operation until the semaphore has been turned through another quarter-revolution by subsequent depression of the button 54.

65 The preferable construction of the sema-

phore is that shown in the drawings, in which a visual enlargement 73 is located on the end of the semaphore-arm to assist the sight by day, whereas a second enlargement 74, having a red glass 75 therein, is carried within 70 the arm 73 and opposite the lantern 76, suspended from the side of the semaphore-box to enable the same to be seen by night. Furthermore, I preferably provide a secondary pair of semaphore-arms 77, rigid with the 75 shaft 8 and at right angles with the arms 7, which are of less length than the latter and carry at their ends blue or yellow glasses 78, which cause the common white light of the lantern to be distinguished from other lights 80 in the neighborhood of cities and call the same to the attention of the engineman on the train.

For the protection of the semaphore-arms, and particularly the upwardly-extending member when in its vertical position, I provide a semicircular hood or cowl 79, which incloses and covers the upper arm and prevents damage by wind and rain. 85

While I have shown in the accompanying drawings the preferred form of my invention, it will be understood that I do not limit myself to the precise form shown, for many of the details may be changed in form or position without affecting the operativeness or utility of my invention, and I therefore reserve the right to make all such modifications as are included within the scope of the following claims or of mechanical equivalents to the structures set forth. 100

Having thus described my invention, what I claim as new, and desire to secure by Letters Patent, is—

1. In a semaphore, the combination of swinging arms, an axle on which they are pivoted, a motor arranged to drive said axle, a pallet-wheel on an extended end of said axle, a second pallet pivotally mounted on a fixed part, an electrically-operated releasing device for breaking engagement between the arms of the said pallet-wheel and pallet, a safety device adapted to operate to actuate the return-signal of the semaphore, a notched wheel, a releasing-click mounted for coöperation with said notched wheel, and a connection between said wheel and the upper arm of said pallet. 110 115 120

2. In a semaphore, the combination of swing-
ing arms, their axle, a motor for turning said
axle, a pallet-wheel carried by the axle, a pal-
let-lever mounted for coöperation therewith,
a secondary axle, a motor for turning the
same, a wheel having a radial tooth mounted
on the secondary axle, a click, a pitman con-
nected with the said wheel and with the pal-
let, means for operating said click, and means
for actuating the click to release the second-
ary axle and permit the rotation of the swing-
ing arms. 120

3. In a semaphore, the combination of swinging arms, their axle, means for turning the 130

- axle, a pallet-wheel carried by the said axle, a pallet-lever for coöperation with the arms of the pallet-wheel, a secondary axle, means for turning the same, a wheel with radial 5 tooth on said secondary axle, a click adapted for coöperation with the tooth of said wheel, connections between said wheel and pallet, means to operate the click, a primary and a secondary circuit-closing device and a signaling 10 device located in the secondary circuit, and means carried by the pallet-wheel for co-operation with the secondary circuit-closing device whereby the operator is assured of the operation of the semaphore.
- 15 4. In a semaphore, the combination of swinging arms, their axle and means for turning the axle, of a pallet-wheel, a pallet-lever mounted for coöperation with said pallet-wheel, a toothed wheel, a connection between 20 the same and the pallet-lever, means for actuating said wheel, a signaling device, means for controlling the same, and a safety device and connections whereby the operator is assured of the operation of the semaphore.
- 25 5. In a semaphore, the combination of swinging arms, an axle for the same and means for turning the axle, of a secondary axle, means for turning the same, coacting means on said axles, for holding the arms against turning, co- 30 acting means on the secondary axle and a pivoted pallet mounted on a stationary part for releasing said arms, a circuit-closing device controlling said means, and a secondary circuit-closing device embodying a spring-actuated bolt and bosses for coöperation therewith, as and for the purpose specified.
- 35 6. In a semaphore, the combination of swinging arms, an axle on which said arms are mounted, a motor adapted to intermittently drive 40 said axle, a pallet-wheel mounted on said axle and having projecting arms, a double-armed pallet the upper arm of which is adapted to engage an arm of said pallet-wheel in one position and the lower arm when in the opposite 45 position, an electromagnet adapted to cause the withdrawal of the upper arm of said pallet, a circuit adapted to energize said electromagnet, a circuit-closing device located in said circuit for completing the same, whereby the 50 successive depression and releasing of said circuit-closing device causes the pallet-wheel to be rotated, a series of bosses projecting from the face of said pallet-wheel, a second circuit-closing device having a depressible bolt 55 located adjacent to said pallet-wheel and adapted to be depressed by said bosses, an electric circuit connected to said second circuit-closing device, and signaling means located in said circuit and at the station where said first- 60 mentioned circuit-closing device is located, whereby said signaling device is caused to be operated by the turning of said arms, substantially as described.
- 65 7. In an electric semaphore, the combination of swinging arms, a horizontal axle on

which they are journaled, a suitable motor connected to said axle to turn the same, a four-armed pallet-wheel mounted on said axle, a two-armed pallet-lever pivoted on a stationary bracket at the side of the pallet-wheel and the 70 upper arm of which normally engages therewith, a secondary axle mounted in stationary journals at the side of the main axle, a motor connected therewith to turn the same, a wheel having a radial tooth mounted on said secondary axle, a click having two members at opposite sides of said wheel adapted to engage said tooth, a pitman connected to said wheel and to said pallet to operate the same, an electromagnet adapted to operate said click, a circuit in 75 which said magnet is located, and a circuit-closing device located in said circuit at a distant point whereby the depression of same will cause said click to be operated to release said secondary axle and the pallet-wheel thereby to be withdrawn to permit the rotation of said swinging arms, substantially as described. 80

8. In an electric semaphore, the combination of swinging arms, a horizontal axle on which they are journaled, a suitable motor connected to said axle to turn the same, a four-armed pallet-wheel mounted on said axle, a two-armed pallet-lever pivoted on a stationary bracket at the side of the pallet-wheel and the 85 upper arm of which normally engages therewith, a secondary axle mounted in stationary journals at the side of the main axle, a motor connected therewith to turn the same, a wheel having a radial tooth mounted on said secondary axle, a click having two members at opposite sides of said wheel adapted to engage said tooth, a pitman connected to said wheel and to said pallet to operate the same, an electromagnet adapted to operate said click, a circuit in 90 which said magnet is located, and a circuit-closing device located in said circuit at a distant point whereby the depression of same will cause said click to be operated to release said secondary axle and the pallet-wheel thereby to be withdrawn to permit the rotation of said swinging arms, substantially as described. 95

9. In an electric semaphore, the combination of swinging arms, a horizontal axle on which they are journaled, a suitable motor connected to said axle to turn the same, a four-armed pallet-wheel mounted on said axle, a two-armed pallet-lever pivoted on a stationary bracket at the side of the pallet-wheel and the 100 upper arm of which normally engages therewith, a secondary axle mounted in stationary journals at the side of the main axle, a motor connected therewith to turn the same, a wheel having a radial tooth mounted on said secondary axle, a click having two members at opposite sides of said wheel adapted to engage said tooth, a pitman connected to said wheel and to said pallet to operate the same, an electromagnet adapted to operate said click, a circuit in 105 which said magnet is located, and a circuit-closing device located in said circuit at a distant point whereby the depression of same will cause said click to be operated to release said secondary axle and the pallet-wheel thereby to be withdrawn to permit the rotation of said swinging arms, a second circuit-closing device located adjacent to the face of said pallet-wheel and having a depressible bolt, a circuit connected with the terminals of said last-named device, a signaling device such as a bell located in said last-mentioned circuit at the operating end of the line, and a series of bosses carried on the face of said pallet-wheel adapted to depress said last-named circuit-closing device at each quarter-revolution of 110 said pallet-wheel, whereby the operator is assured of the operation of the semaphore, substantially as described. 115

115 10. In witness whereof I have hereunto set my hand in the presence of two witnesses.

DONA BOISVERT.
